UNITED STATES PATENT OFFICE.

CHARLES H. BRADSHAW, OF BATTLE CREEK, MICHIGAN.

CARD GAME.

1,290,498.

Specification of Letters Patent.

Patented Jan. 7, 1919.

Application filed May 25, 1918. Serial No. 236,576.

To all whom it may concern:

Be it known that I, CHARLES H. BRADSHAW, a citizen of the United States, residing at Battle Creek, in the county of Calhoun and State of Michigan, have invented certain new and useful Improvements in Card Games; and I do hereby declare the following to be a full, clear, and exact description of the invention, such as will enable others skilled in the art to which it appertains to make and use the same.

The object of the invention is to provide an entertaining and instructive card game apparatus based upon the operations and equipment of land and naval or military and marine forces and equipment with a view to indicating and to a degree emphasizing the relative or comparative values of forces of different sizes and characters and equipment of different kinds, offensive and defensive, which enter into and constitute factors in determining the outcome of military and naval contests, and with this object in view the invention consists in a combination and relation of parts and designations thereof hereinafter fully explained, it being understood that changes in form and details may be resorted to within the scope of the appended claims, without departing from the spirit of the invention.

In the drawings:

Figures 1 to 15, inclusive, represent cards belonging essentially to what may be termed the army suit as designating corps or bodies of men and equipment which are used more particularly in land operations.

Figs. 16 to 27, inclusive, represent cards which belong or relate more particularly to what may be termed the navy suit or to men and equipment which are usually allotted to or employed in connection with naval operations.

Figs. 28 and 29 represent cards which may arbitrarily be designated as "wild" or as belonging to or adapted to be used in either suit or in operations occurring either on land or on water.

The cards of the suit, of which any desired number, but preferably a specified and understood number such as one hundred and seventy-two, may be employed, are divided generally into two suits which may be understood as respectively army and navy suits, and the units or elements or cards of which are distinguishably designated by reference to corps or bodies of men and articles of equipment

employed respectively in land and naval operations. For example, in the army suit will be found cards designated as "infantrymen, cavalrymen, light artillery, heavy artillery, tanks, barbed wire entanglements, poison gas, gas masks, supply train, ammunition train, aeroplane, anti-aircraft gun and the like," while in the navy suit may be found cards designated, for example, as "marines, 60 troop ship, troop ship convoyed by submarine chasers, supply ship, battleship, torpedo boat, torpedo boat destroyer, submarine, and the like." Moreover, the several cards of each suit are distinguishably designated not only by the names as above enumerated, and the list of which of course may be extended to any desired degree, but by designations of value, preferably located near the centers of the cards and represented in the drawings 65 by the numerals 1, 2, 3, 4, 5 and so forth. These value designating numerals or characters are supposed to represent the comparative values of the bodies of men or equipment represented by the corresponding 70 cards when used respectively in land and naval engagements, when, in the course of play, such cards fall in the same trick or are played in opposition to each other by the 75 several participants in the game.

Moreover, certain cards, for example, such as those shown in Figs. 28 and 29, may be played in tricks with cards of either suit and for that reason may be termed "wild" as above noted, and while belonging for instance more particularly to the army suit and designed to be used more especially in tricks relating to the army suit, may be employed in tricks including elements or units of the navy suit and may have the same 80 value relatively in either suit or may have different values according to whether played in the army suit or the navy suit. The card representing retreat, for example, shown in Fig. 29, may have different values according 85 to whether played during the game or as the last card of the holder, and may also have different values according to whether played in the army suit or the navy suit. Also the card designated as "marines" in Fig. 16 may 90 have a designated and specified value such as three when used in its own suit, namely, the navy suit, to which it properly belongs, but may be used in the army suit and when so used may have either the same or a different value numerically or as to the outcome of the game or as to its neutralizing 95 100 105 110

or taking value in regard to other cards, as may be preferred and as may be specified by the rules under which the game is played.

It is deemed unnecessary to include herein a detailed description of any particular game or series of games which may be played by means of cards distinguishably designated as indicated as the variety is almost unlimited, but by adopting, as indicated in the drawings, an arbitrary value in play for the several cards when used in certain sequence or relation and in corresponding suits, and assuming that either the same or different values attach to the playing of such cards if used in the suits to which they belong or in the other suit and whether used in sequence in a given order, that is either in advance or following a corresponding or opposing card of the same suit, an unlimited number of combinations may be produced, and at the same time the general values of the articles or equipments ordinarily found in connection with army and navy forces will be indicated and impressed upon the minds of the participants of the game in such a way as to have an educational value.

Having described the invention, I claim:

1. A card game having suits of which the cards are distinguishably designated by reference to corps of men and equipment employed respectively in land and naval military operations, the cards of each suit being distinguished by designations of numerically different bodies of men and relatively important offensive and defensive elements of equipment in the respective services represented by the suits, and having comparatively different values in play.

2. A card game having suits of which the cards are distinguishably designated by reference to corps of men and equipment employed respectively in land and naval operations, the cards of each suit being distinguished by designations of numerically

different bodies of men and relatively important offensive and defensive elements of equipment in the respective services represented by the suits, and having comparatively different values in play, the values of certain units being determinable by the sequence in use with reference to other units.

3. A card game having suits of which the cards are distinguishably designated by reference to corps of men and equipment employed respectively in land and naval operations, the cards of each suit being distinguished by designations of numerically different bodies of men and relatively important offensive and defensive elements of equipment in the respective services represented by the suits, and having comparatively different values in play, and one of the suits including a class of units adapted for interchangeable use with reference to the other units of both suits.

4. A card game having suits of which the cards are distinguishably designated by reference to corps of men and equipment employed respectively in land and naval military operations, the cards of each suit being distinguished by designations of numerically different bodies of men and relatively important offensive and defensive elements of equipment in the respective services represented by the suits, and having comparatively different values in play, and one of the suits including a class of units adapted for interchangeable use with reference to the other units of both suits and having different values in play determinable by the suit of the unit against which it is used.

In testimony whereof I affix my signature in presence of two witnesses.

CHARLES H. BRADSHAW.
